(57) **CLAIM**

The ornamental design for a fan with light, as shown and described.

DESCRIPTION

FIG. 1 is a first perspective view of the fan with light showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines immediately adjacent the shaded areas represent the bounds of the claimed design while all other broken lines are directed to portions of the fan with light; the broken lines form no part of the claimed design.

1 Claim, 7 Drawing Sheets
